ANNOUNCING METHOD AND SYSTEM

Leslie J. Anderson, Indianapolis, Ind., assignor to
Radio Corporation of America, a corporation of
Delaware

Application January 9, 1945, Serial No. 571,969

4 Claims. (Cl. 179—1)

This invention relates to signal transmission systems, and particularly to a public address or announcing system for use in factories and the like where extraneous noise, such as that from machinery, is present in the signal reproducing areas.

Sound reinforcing and public address systems are well-known in the art, these systems consisting of a sound pickup device, such as a microphone, an amplifier, and one or more loud speakers positioned in the area where it is desired to reproduce the signal picked up by the microphone. In large manufacturing plants, speakers are distributed in the various locations so that announcements may be made to the employees or a particular person may be called thereover. It is obvious that in such an announcing system certain speakers may be located in areas where operating machinery produces a high noise level either continuously or periodically. Since the announcer at the microphone is unaware of the noise level at the various positions, the output of the speakers is sometimes too low for the announcement to be heard above the noise.

The present invention is directed to an announcing system wherein the noise level in the speaker area automatically controls the output of the loud speakers regardless of the level of the input signal. Thus, the signal will always be loud enough to be heard by those in the area, since its level is raised by and in accordance with the noise in that particular area. The invention also embodies means for preventing regeneration or feedback between the speakers and the controlling microphone.

To accomplish the above results, I utilized the general principle disclosed and claimed in my Patent No. 2,189,306 of February 6, 1940, wherein a portion of the output from the announcing microphone is rectified to control the gain of the signal amplifier. In this patented system, the signal channel amplifier has a minimum gain during no signal input, but when the signal is impressed on the microphone, the gain is raised to normal by a rectified portion of the signal. To eliminate feedback during the period when the signal amplifier is at normal gain, a high pass filter is used in the signal channel and a low pass filter is employed in the control channel.

The present invention is an improvement over previously known announcing systems by utilizing a microphone pickup in the area of sound reproduction by the loud speakers, the level of certain frequencies of the sound in this area

controlling the gain of the signal amplifier. To prevent feedback, an improvement over my patent above mentioned is employed wherein a band pass filter is used in the signal channel and a band elimination filter is used in the control channel. By this arrangement, noise frequencies which usually lie in the lower and upper portions of the audio spectrum are used to control the gain of the signal amplifier, while the output of the speakers is limited to frequencies in the remaining central portion of the spectrum which do not influence the control signal. Thus, the control of the amplification will be due to the noise level and not to the signal level in the same area.

The principal object of the invention, therefore, is to facilitate the reproduction of sound in high noise level areas.

Another object of the invention is to provide an improved method of and system for reproducing sound in areas having high or varying noise levels.

A further object of the invention is to provide an improved method and system of preventing feedback between acoustically coupled sound pickup and reproducing devices.

A still further object of the invention is to provide an improved public address or announcing transmission system wherein the output of the sound reproducing devices are under the automatic control of the noise levels in the respective areas of sound reproduction.

Although the novel features which are believed to be characteristic of this invention will be pointed out with particularity in the appended claims, the manner of its organization and the mode of its operation will be better understood by referring to the following description read in conjunction with the accompanying drawing forming a part hereof, in which:

Fig. 1 is a schematic diagram of an announcing system embodying the invention, and

Fig. 2 is a graph showing an adjustment of the filters in the respective portions of the system.

Referring now to Fig. 1, a signal pickup microphone 6 is connected to an amplifier 8. The output of the microphone may also be connected to the other amplifiers in other signal channels as indicated by the dotted lines 3. The output of amplifier 8 is connected through transformer 9 to a pentode variable gain amplifier tube 10. The output of tube 10 is connected through a capacity resistance network composed of condensers 12 and 13 and resistors 14 and 15 to a triode amplifier 17, the output of which is impressed

on a transformer 18 over condenser 19. The regular grid biasing resistors 20 and 21 shunted by bypass condensers 22 and 23 are shown in the cathode circuits of the respective tubes 10 and 17. Anode potential for tube 17 is supplied over resistor 24.

The signal amplified in amplifier 17 is reproduced by one or more loud speakers such as shown at 26 and 27. The transformer 18 does not directly feed the speakers 26 and 27, these elements being interconnected by a band pass filter 28 composed of two series resonant, series connected sections and a parallel resonant shunt connected section. One series section comprises a condenser 30 and inductance 31, and the other series section comprises an inductance 32 and a condenser 33. The parallel shunt element is composed of an inductance 35 and a condenser 36, and is connected from a point between the series sections and the other side of the line.

Located in the area in which sound is reproduced by the speakers 26 and 27 is a control pickup microphone 40 which is connected to an amplifier tube 41 through a transformer 42 and a band elimination filter 44. This band elimination filter is composed of two parallel resonant sections connected in series, one section being composed of an inductance 46 and a condenser 47, and the other section being composed of an inductance 48 and a condenser 49. To complete this filter, a series resonant section, composed of a condenser 51 and an inductance 52, is connected from a point between the parallel resonant sections and the other side of the line.

The output of amplifier 41 is impressed on a full wave rectifier composed of vacuum tube rectifiers 55 and 56 over a transformer 57, the output being passed through a capacity-resistance filter to a load resistor 60. The capacity-resistance filter is composed of three resistors 61, 62, and 63, and two condensers 64 and 65, these elements being given values to provide the proper timing desired during increases and decreases in the control signal.

It will be noted that the control grid of variable gain amplifier 10 is connected through the secondary of transformer 9 and the rectifier load resistor 60 and back to the cathode of tube 10 through fixed bias resistor 20. In this manner, variations in current through the resistor 60 will vary the bias on tube 10 and thus vary its gain. The circuit is so arranged that increases in the amplitude of the signal detected by the microphone 40 will reduce the bias on tube 10 to increase its gain, so that the output of the signal channel at speakers 26 and 27 will be increased proportionately.

To prevent the output of the speakers 26 and 27 from being detected by microphone 40 and thus cause regeneration, feedback, or singing, the two filters 28 and 44 are employed. Referring now to Fig. 2, the characteristics of the two filters are illustrated, filter 28 being a band pass filter passing frequencies from approximately 400 to 6500 cycles per second. This frequency range is one which will provide the signal with good intelligibility for speech transmission and adequate quality for the transmission and reproduction of music. Filter 44 is a band elimination filter and eliminates the portion of the audio frequency spectrum lying approximately between 400 and 6500 cycles, as indicated by the dotted lines, while passing frequencies below 400

and above 6500 cycles per second. It has been found that this proportioning of the frequency bands will permit the control circuit to raise the level of the signal channel in substantially direct proportion to the increase in noise in the sound reproducing area, while preventing feedback in the system.

As mentioned above, other signal channels may feed other listening areas as indicated by the dotted lines 8, these other channels either having similar automatic level control circuits in case the speakers are in noise areas, or having solely an amplifier or fixed gain in case the sound is reproduced in silent areas, such as offices or similar locations.

I claim as my invention:

1. In a system including an amplifier connected between a signal source and a reproducing device, the combination of a band pass filter 20 connected between said amplifier and said reproducing device for restricting the input to said reproducing device to impulses of frequencies lying in a predetermined band between substantially 400 and 6500 cycles per second, a pickup device, a rectifier, a band elimination filter for

25 restricting the output from said pickup device as impressed on said rectifier to impulses of frequencies lying below 400 and above 6500 cycles per second, and means for directly controlling 30 the bias on said amplifier with the output of said rectifier.

2. The method of maintaining a substantially constant signal to noise ratio in a listening area served by a sound reproducer and subject to

35 varying noise levels comprising selecting for reproduction a predetermined band of frequencies in said signal lying between 400 and 6500 cycles per second, detecting sound frequencies in said area lying below 400 and above 6500 cycles per

40 second, and directly controlling the level of reproduction of said signal frequencies by the amplitude of said detected sound frequencies.

3. The method of increasing the level of reproduction of a signal as the noise level in the reproduction area increases without causing regeneration comprising reproducing only a predetermined band of frequencies in said signal lying between 400 and 6500 cycles per second, detecting only the sound frequencies lying below 400 and above 6500 cycles per second, and increasing the level of signal reproduction directly in accordance with the amplitude of the products of detection.

4. An announcing system comprising a sound pickup device, an amplifier for the output of said device, a reproducer for translating the output of said amplifier into sound waves, a band pass filter connected between said reproducer and amplifier for suppressing the impression of frequencies lying below 400 and above 6500 cycles per second in the output of said device on said reproducer, a second sound pickup device acoustically coupled to said reproducer, a rectifier for the output of said second device, a band elimination filter connected between said rectifier and said second pickup device for suppressing the impression of frequencies lying between 400 and 6500 cycles per second on said rectifier, and means for connecting said rectifier to said amplifier for directly controlling the gain of said amplifier in accordance with the amplitude of the output of said rectifier.

LESLIE J. ANDERSON.
